US0D1021404S

(12) **United States Design Patent** (10) Patent No.: **US D1,021,404 S**
(45) Date of Patent: ** Apr. 9, 2024

(54) **TACKLE BAG WITH LURE RETENTION PANEL**

(71) Applicant: **Thousand Oaks Corp.**, Irwindale, CA (US)

(72) Inventor: **Tyler Fernandes**, Irwindale, CA (US)

(73) Assignee: **Evolution Outdoor, LLC**, Kilgore, TX (US)

(**) Term: **15 Years**

(21) Appl. No.: **29/777,817**

(22) Filed: **Apr. 8, 2021**

(51) LOC (14) Cl. **03-01**

(52) U.S. Cl.

USPC **D3/260**

(58) **Field of Classification Search**

USPC D3/273, 276, 279, 283-290, 301, 230, D3/254, 260, 232, 245, 904-905; D7/607, 709

CLAIM

The ornamental design for a tackle bag with lure retention panel, as shown and described.

DESCRIPTION

FIG. 1 is a front right perspective view of the tackle bag with lure retention panel having both the lure retention panel cover and front lower pocket open;

FIG. 2 is a front left side perspective view of the tackle bag with lure retention panel, having the front lower pocket open;

FIG. 3 is a top view of the tackle bag with lure retention panel having the lure retention panel cover open;

FIG. 4 is a bottom view of the tackle bag with lure retention panel having the lure retention panel cover open;

FIG. 5 is a front view of the tackle bag with lure retention panel having both the lure retention panel cover and front lower pocket open;

FIG. 6 is a front view of the tackle bag with lure retention panel having the lure retention panel cover open and the front lower pocket closed;

FIG. 7 is a rear view of the tackle bag with lure retention panel having the lure retention panel cover closed;

FIG. 8 is a left side view of the tackle bag with lure retention panel having the front lower pocket open;

FIG. 9 is a right side view of the tackle bag with lure retention panel having the lure retention panel cover closed and the front lower pocket open;

FIG. 10 is a right side view of the tackle bag with lure retention panel having both the lure retention panel cover and the front lower pocket open; and,

FIG. 11 is a partial front perspective view of the tackle bag with lure retention panel showing the front lower pocket open and viewing into the area within the tackle bag with lure retention panel.

The various components of the article and boundaries shown in broken line illustrations are shown in broken lines for illustrative purposes only and form no part of the claimed design. Any unshaded surfaces within the broken line boundaries form no part of the claimed design. The broken lines showing zipper assemblies, zipper tracks, handles, straps, and lure retention slots form no part of the claimed design. The short dashed lines in FIG. 11 define the fragment shown only and do not form any part of the claimed design. The remaining broken lines represent stitching that forms no part of the claimed design.
